Des. 234,370
Patented Feb. 18, 1975

234,370

FLASH UNIT FOR A PHOTOGRAPHIC CAMERA

Robert Oberheim, Neu-Isenberg, Schoenbornring, Germany, assignor to Braun Aktiengesellschaft, Frankfurt am Main, Germany

Filed Sept. 13, 1972, Ser. No. 288,663

Claims priority, application Germany Mar. 17, 1972

Term of patent 14 years

Int. Cl. D16—05

U.S. Cl. D61—1 F

FIG. 3

FIG. 2

FIG. 1

FIG. 4

FIG. 5

FIG. 6

FIG. 1 is a front elevational view of a flash unit for a photographic camera showing my new design;

FIG. 2 is a rear elevational view thereof;

FIG. 3 is a left side elevational view thereof;

FIG. 4 is a top plan view thereof;

FIG. 5 is a bottom plan view thereof; and

FIG. 6 is a right front perspective view thereof.

I claim:

The ornamental design for a flash unit for a photographic camera, substantially as shown.
